SLICING MACHINE

John A. Pinaud, Tampa, Fla.

Application September 14, 1948, Serial No. 49,149

3 Claims. (Cl. 146—102)

1

This invention relates to improvements in manually operated machines for cutting into slices, of varying thickness, of cooked meats, sausages, cheese and products of a similar nature and has particular reference to a machine of the said character wherein a circular knife is mounted upon a frame or base and rotated by the action of a reciprocally moving arm and mechanism upon the said arm which carries, co-acting therewith, a set of jaws comprising a hopper for holding the product to be sliced. The forward and downward movement of the said arm brings the product to be sliced into contact with the edge of the said rotating knife and away from same when the handle is retracted. The said hopper comprises two jaws, one of which is immovably fixed to the lower, inner end of said arm in a manner as will be hereinafter described, and pivotally attached to the stationary frame at base. The second jaw is pivotally attached to the said fixed hopper jaw but operates with the said arm and holds the product to be sliced in the hopper during the slicing movement and releases the said product at a predetermined point in the retractive movement of the parts.

One object of this invention is to provide a manually operated slicing machine of the character described and which comprises a minimum number of parts, making same compact, light in weight and particularly desirable for household use.

Another object of this invention is the provision of a machine of the character described in which the parts are so designed and assembled that they may be readily and quickly cleaned without dismantling or disassembling.

A further object of this invention is to provide a manually operated slicing machine of the character described wherein a hopper, having holding jaws is employed. The said hopper being adapted to hold the product to be sliced and being actuated by a reciprocally moving arm which is pivotally attached to the base of the machine.

A still further object of this invention is the inclusion therein of a spring means for holding the product to be sliced in the hopper during the cutting action and releasing the said product when the cutting action has been completed.

Another object of this invention is the inclusion therein of a gauge plate to fix the thickness of the slice to be cut and novel means for adjusting the said gauge plate.

A further object of this invention is the inclusion therein of a rack and ratchet driving means for rotating the said knife, the said rack being

2

actuated by the reciprocal movement of the said operating handle.

A further object of this invention is the means provided therein, for changing the movement of the rack to reduce or accelerate the rotating speed of the knife.

A still further object of this invention is the provision of a device in which the constituent elements are so arranged structurally and functionally as to assure improved results with materials and members which may be manufactured at reasonable cost, may be easily assembled and which will be efficient in operation with minimum wear to the parts.

15 The invention possesses other objects and features of advantage, some of which, with the foregoing will be set forth in the following description and in the claims wherein parts will be identified by specific names for convenience but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

20 The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings, in which:

25 Fig. 1 is an end or rear view in elevation of the slicing machine.

Fig. 2 is a side elevation of same.

30 Fig. 3 is a top view of same.

35 Fig. 4 is a side view, partly broken away, of the machine, opposite to the side shown in Fig. 2 and shows the apparatus tilted so that the plane of the circular knife and gauge-plate is at 90° to the horizontal plane. This figure also shows a modification which will be hereinafter described.

40 Fig. 5 is an enlarged detail of a part of the apparatus.

45 Fig. 6 is a section of same taken along line 6—6 of Fig. 5.

50 Fig. 7 is an enlarged fragmentary detail of the modification shown in Fig. 4 and is a partial section taken along the line 7—7 of Fig. 4.

Fig. 8 is a schematic view of a part which will be hereinafter described.

Fig. 9 is a fragmentary detail of a part and will be hereinafter described.

Fig. 10 is a side elevation, partly broken away, and shows the working parts fully retracted.

Fig. 11 is an end elevation of Fig. 10 and shows a portion in section and will be hereinafter fully described.

Fig. 12 is a section through the knife mounting 10 and is taken along the line 12—12 of Fig. 10.

Fig. 13 is a side view, partly broken away, showing the working parts in its advanced cutting position.

Fig. 14 is a similar view, partly broken away 15 and shows another position of the operating parts.

Referring in detail to the parts, 11 designates a supporting frame formed with an inclined side member 12 having a recessed portion which forms a pocket 13 within which a circular knife or cutter 14 is rotatably mounted. Lugs 15 and 16 are formed upon the base of said supporting frame 11 to which the lower ends 17 and 18 of a hopper jaw 19 are pivotally attached. An operating arm 20 having a handle 21 and legs 22 and 23 is attached against the under side of said hopper jaw 19 and is held in place by means of a rivet 24 formed upon the leg 23 of the said operating arm 20. The said rivet 24 is adapted to engage within a corresponding orifice 25 in the leg 18 of the said hopper jaw 19. A second rivet 26 formed upon the leg 17 of the said hopper jaw 19 engages through an orifice 27 in the leg 22 of the said operating arm 20. (Figs. 8 and 11.)

The hopper legs 17 and 18 are each formed with studs or bosses 27 and 18 respectively which are flattened along part of their peripheries as at 29 and 30 and are adapted to engage the legs 22 and 23 of the said operating arm 20. The said flattened portions of the bosses, together with the rivets 24 and 26 coact to hold the said operating arm securely upon the hopper jaw 19. The said hopper jaw 19 and its connected operating arm 20 are adapted to oscillate as a single unit about the pivotal connections 15 and 16. A pin 31 being employed to complete the connection.

A second hopper jaw 32 having legs 33 and 34 is pivotally attached to the legs 17 and 18 respectively by means of a pin 35 around which a spirally wound spring 36 is mounted. The said spring has a downwardly extending arm 37 the end of which engages a slot 38 formed in a web formation 38' which unites the two said legs 17 and 18 of the hopper jaw 19. The opposite end of the spiral spring 36 has an upwardly turned arm 39, the upper end of which is turned out at a right angle 40, to engage in a slot 41 (Figs. 4 and 9) formed in a hopper jaw 32. The said spiral spring 36 exerts a force between the hopper jaws 19 and 32 which tends to bring them normally together and hold a product to be cut by the rotating knife. The dot-dash lines in Figs. 10, 13 and 14 indicate a food produce which is to be sliced.

The angular end 40 of the spiral spring 36 is adapted to act as a bumper and limit the retractive movement of said hopper jaw 32. This limitation of movement is accomplished by the contact of the spring with a lug 42 formed upon an arcuate flange 43 upon the frame 11. A gauge plate 44 is adapted to rest upon the said arcuate flange 43 and is adjusted relatively with the rotating knife, by means of a four point helical mechanism actuated by means of a hand knob

45 (Fig. 11) which engages a cylindrical member 46, and enables full adjustment of the gauge plate by one quarter turn of the knob. The said cylindrical member 46 is rotatably mounted within a cup shaped portion 47 of the frame 11 and is rotatable therein. The inner edge of said cylindrical member is formed with four helical surfaces 48 which contact complementary helical surfaces 49 formed upon an annular flange 50 in turn integrally formed upon the gauge plate 44. A spring 51 is adapted to hold the parts together as clearly shown in Fig. 11, the spring being assembled in torsion to oppose the torsional component of the lineal spring force, due to the angularity of the helical surfaces. The hand knob 45 is keyed to the said cylindrical member 46 by means of pins 52 which engage in grooves 53. As shown in Fig. 11, the gauge plate 44 is set to cut a slice of minimum thickness. By turning the knob 45, the said gauge plate may be moved outwardly until the opposing helical surfaces are brought closely together at which point a slice of maximum thickness may be cut by the rotating knife 14.

The knife and its associated drive mechanism mountings will be best understood by the following description considered in connection with the illustrations in Figs. 5, 6, 10 and 12. A boss or stud 54, having a central bore 55, is shown in Figs. 6 and 12 and is formed in the pocket 13 of the frame 11. Within the said bore 55, there is a bushing 56 and within the bushing is an internally threaded tubular member 57 to which the said knife 14 is attached by means of the counter-sunk screw 58. The said tubular member 57 is held upon the boss 54 by means of a screw 59 and interposed washer 60. Rotatably mounted over the said tubular member is a ratchet member 61 having pawl elements 62 held in recesses or pockets 63 (Fig. 5). The ratchet member 61 is provided with pins 64 by means of which the said ratchet is tied to the knife 14 as clearly shown in Figs. 6, 10 and 12. The said ratchet 61 is given rotary movement by means of a gear 65 having internal ratchet teeth 66 with which the pawls 61 engage. A flat V-shaped spring 67 being employed to keep the said pawls normally in contact with the said ratchet teeth 66.

50 The said gear 65 is activated or rotated by means of a rack 68 which engages the gear 65 and is held in alinement therewith by the idler or guide pulley 69 (Figs. 10 and 12). When the rack 68 moves in the direction indicated by the arrows X, (Figs. 5 and 10), the gear 65 and its associated ratchet 61 and knife 14 will rotate in the direction indicated by the arrows X'. When the rack 68 is retracted or moves in the opposite direction, the gear 65 will turn in a reverse direction to that above indicated while the knife 14 will continue in its original rotary movement or come to a stop.

55 Reciprocal movement is given to the rack 68 through its attachment at 70 or 71, which attachment is fixed by the reciprocating pin 72 or 73 clearly shown in Fig. 11 wherein the pin 73 is shown in engagement with the rack 68 at 71, the pin 72 being retracted by a rocker arm 74 pivoted at 75 to the web 38'. Obviously, with this rocker arm connection, when the pin 73 is pushed into action the pin 72 moves out of action as indicated. When the pin 73 is pushed in and connection is made at 71, between the rack 68 and hopper jaw 19 the relative position of the said rack is as 70 shown in Figs. 10 and 13. Fig. 10 shows the re-

tracted position of the operating parts and Fig. 13 shows the position of the operating parts at the end of the forward or cutting movement. The connection of the rack 68 with the hopper jaw at 71 as just described imparts a high speed rotation to the knife 14. When, however, a slower speed of rotation to the knife is desired, the parts are retracted until the rack 68 rests in the stop 76 as at 77. When the operating parts are in the position just described, the pin 72 is pushed in to make a connection between the rack 68 and hopper jaw 19 at 78 at the same time disengaging the said rack and hopper jaw at 71. With this last named connection of the rack and the hopper jaw the operating parts, when the operating arm 20 has been moved forward, assume the position shown in Fig. 14. This arrangement imparts a slow speed to the cutting knife 14 and is desirable for slicing certain types of products. If desired the pin 72 may be shortened so that it does not connect to the rack 68 when pushed in, thus allowing the said rack and the knife 14 to remain stationary when the operating arm is moved forward. In which case the pin 72 serves only to cause retraction of pin 73.

To prevent the accidental displacement of the pins 72, 73, the pin 72 is formed with annular grooves 79 and 80 which engage the lower leg 37 of the said spring 36.

In Figs. 4 and 7 there is shown a modified form which dispenses with the rack 68 and driving gear 65. In this embodiment the gear 65 is replaced by a cylindrical member or drum 81 which rotates freely about the ratchet member 61 and has internal ratchet teeth similar to the teeth 66 of the gear 65. A spiral spring 82 is attached at one end to the said drum 81 as at 83 (Fig. 4) and at its outer end is attached to a pin 84 upon a lug 85 which is formed upon the stud 54. A wire, flexible cable or cord 86 is wound over the said drum at one end and at its other end is attached to a pin 87 upon the leg 18 of the hopper jaw 19. The said cord 86 passes around an idler or guide pulley 88 which is rotatably mounted upon a boss formed upon the frame 11.

Suitable markings 89 may be provided upon the cup shaped portion 47 on the frame 11 to indicate various positions or settings of the gauge plate 44 and a setting mark 90 may be provided upon the knob 45 to aline with the markings 89 as the knob is turned.

A portion of the wall of the pocket 13 is cut away as at 91 (Fig. 2) to allow the slices, as they are cut from the food product in the hopper, to leave same and fall upon a shelf 92 from where they are discharged or taken from the machine.

A slideable plate 93 may be suspended from the upper edge of the said fixed hopper jaw 19 by means of a hooked end 94 and affords a means whereby small end sections of food products may be fed for slicing.

5 I claim:

1. A manually operated slicing machine for cutting slices from food products, comprising a base and supporting member, a circular knife rotatably mounted thereon, an operating arm mounted upon said base and supporting member and reciprocally movable thereon, a hopper having a fixed and a movable jaw mounted upon said operating arm, the said hopper being adapted to hold a food product and the said movable jaw coordinating with the fixed jaw adapted to hold the said food product in place, a rack pivotally attached at one end to the said fixed jaw, a gear rotatable upon the frame and activated by the said rack, a pawl and ratchet upon the said rotatably mounted knife coordinating with said gear and rack to rotate the said knife, a spring means engaging between the said fixed hopper jaw and movable hopper jaw adapted to hold the movable hopper jaw in gripping contact with a food product in said hopper and a hand hold upon the said reciprocally mounted operating arm to move same to bring the food product into slicing contact with the said rotating knife.

2. The slicing machine as set forth in claim 1, wherein the said rack has interchangeable pivotal connection with the said hopper to change the speed of rotation of the said knife.

3. The slicing machine as set forth in claim 1, wherein a stop is formed upon the said base and supporting member and adapted to engage the said movable hopper jaw to limit its retracting movement and release its hold upon the food product in the hopper.

JOHN A. PINAUD.
